(57) **CLAIM**

The ornamental design for a foldable pizza box, as shown and described.

DESCRIPTION

This application is a continuation-in-part of U.S. patent application Ser. No. 29/682,719 filed on Mar. 7, 2019. The above identified patent applications are herein incorporated by reference in their entirety to provide continuity of disclosure.

FIG. 1 depicts a perspective view of a foldable pizza box according to the present invention.

FIG. 2 depicts a front elevation view of the foldable pizza box.

FIG. 3 depicts a rear elevation view of the foldable pizza box.

FIG. 4 depicts a left elevation view of the foldable pizza box.

FIG. 5 depicts a right elevation view of the foldable pizza box.

FIG. 6 depicts a top plan view of the foldable pizza box; and, FIG. 7 depicts a bottom plan view of the foldable pizza box. The dotted lines between the shade lines in FIGS. 1, 2, 3, 6, and 7 represent perforations and form part of the claimed design.

The dot-dash lines in the Figures show portions of the foldable pizza box which form no part of the claimed design.

1 Claim, 4 Drawing Sheets
